UNITED STATES PATENT OFFICE

2,107,860

CHROMATIC BLENDER

Reginald Gilbert, San Francisco, Calif.

Application February 8, 1937, Serial No. 124,717

5 Claims. (Cl. 40—130)

This invention relates to improvements in chromatic blenders and more particularly to mechanical means for reflecting variable shades of coloring.

5 An object of this invention is to produce an everchanging shading and blending effect in colors without a sharp definition of any one color.

Another object is to give depth or third dimensional effects to the shaded blending of basic 10 colors.

Another object is to attract and hold the attention of the observer for a considerable period by means not immediately comprehensible, so that he will give close attention to the changing 15 shades of color and any advertising matter associated therewith.

Other objects and advantages will appear as the description progresses.

Broadly stated the invention consists of arranging a variety of basic colors on a plurality 20 of three dimensional areas, driven in planetary relation to each other around a common center of rotation.

In this specification and the accompanying 25 drawings the invention is disclosed in its preferred form. But it is to be understood that it is not limited to this form because it may be embodied in other forms within the purview of the claims following the description.

30 In the two sheets of drawings:

Fig. 1 is a front elevation partly in vertical section of a chromatic blender constructed in accordance with this invention.

Fig. 2 is a plan view partly in vertical section 35 of the same.

Fig. 3 is an enlarged vertical section taken on the line III—III in Fig. 1 showing the construction details of the chromatic blender.

Fig. 4 is a similar view of the same with modified illumination means.

In detail the construction illustrated in the drawings comprises the base 1, having a suitable enclosure 2 thereon. The advertising front 3, which may be of glass, has a transparent portion 45 or opening 4, disclosing the optic field of the chromatic blender, see Fig. 1. Or the blending wheel may be extended forward of the front 3 as in Fig. 3 for smaller units for show windows and interior displays.

50 The bearing strut 5 mounted upon the base 1 has the separated antifriction bearings 6 and 7 mounted therein. The shaft 8 is mounted in these bearings and has the forward extension on the outer end of which the hexagonal hub 9 is fixed. The blending wheel comprises the radial

studs 10 fixed in this hub and each has a bevel pinion such as 11 freely rotatable thereon.

The plurality of color cones 12 having the hubs 13 are fixed to their respective bevel pinions 11 and are freely rotatable upon their respective 5 studs 10 upon which they are held by the end nuts 14. Six color members 12 are shown but any suitable number may be used. They may be cylindrical, spherical or various shapes adapted to give the third dimensional effects as herein- 10 after more fully described.

The color wheel 9—10 and the cones 12 mounted thereupon revolve with the shaft 8 which is driven by the pulley 15 fixed thereon and belted at 16 to the driving pulley 17 on the shaft of 15 the motor 18 which is mounted upon the base 1, see Fig. 2.

In Fig. 3 the sleeve 19 has the master bevel gear 20 fixed in the end thereof and rotatable on the shaft 8. The pulley 21 is fixed to the 20 opposite end of the sleeve and has the bushing 22 pinned thereto at 23 and freely revolvable on the shaft 8 adjacent the pulley 15. The master gear 20 meshes with all the bevel pinions 11. The pulley 21 is belted at 24 to the driving pulley 25 17 of the motor.

The exposed areas of the several cones 12 are coated with several basic colors, such as the primary colors red, yellow and blue, preferably arranged in spiral bands such as 25, 26 and 27 on 30 each cone, see Fig. 1. Thus arranged on the cones the basic colors overlap in coming into and receding from view, to aid in the persistence of vision in the human eye which gives a very soft shading effect in passing from one dominant 35 shade to the next.

In the modification shown in Fig. 4, the shaft 8 is hollow and has the conduit 28 therethrough to shield the cord 29 supplying current for the electric light 30 in a socket on the end of the 40 conduit. The conduit 28 is fixed in the bracket 31, attached to the strut 5 to hold the conduit against rotation with the shaft 8. The end of the lamp 30 is silvered down to its diameter or otherwise provided with a reflector to direct its 45 light against the revolving wheel of cones.

The lights 32 and 33 are mounted upon the base 1 and adapted to illuminate the cone wheel from below. An excess of illumination tends to diminish the soft velvety effect produced by the 50 cone wheel. Varied effects can be accomplished by basic color alternatives and light intensity.

The invention operates substantially as follows:

The motor 18 drives the shaft 8 which rotates the radial studs 10 around the axis of the shaft. 55

The pulley 21, rotates the ring gear 20 which synchronously sets up a planetary revolution of the cones 12 on their respective studs 10. The rotation of the cones brings their spirally arranged bands of contrasting colors 26-28 into juxtaposition with the similarly moving bands on the adjacent cones 12.

The rotating wheel plus the planetary movement of the cones produces an infinite variety of color blendings and shading. The pulleys 15 and 21 being of different diameters and driven by the pulley 17 of one diameter, the ratio differential sets up color combinations in permutations of such magnitude that the chromatic combinations continue to vary for a long period of time before repeating.

I am aware that flat disks having contrasting color patterns thereon and movable relative to each other for chromatic effects have been known.

But to the best of my knowledge the third dimensional effects of the present invention have been unknown heretofore. The curved planes of the color members 12 give a degree of depth to the chromatic blendings which is hypnotic in its fascination to the beholder, giving a sense of relaxation and tranquility of probable therapeutic value.

While the studs 10 have been shown perpendicular to the shaft 8, they may be arranged obliquely thereto, so that the wheel as a whole may be conical as well as the color members; this gives a very attractive Christmas tree effect.

Having thus described this invention, what is claimed and desired to secure by Letters Patent is:

1. A chromatic blender including a rotatable wheel having radial studs; conical color members rotatable on said studs and having contrast-

ing color bands arranged spirally on their exposed areas; and means for rotating said color members synchronously with said wheel.

2. A chromatic blender including a rotatable wheel having radial studs thereon; conical color members rotatable on said studs and having contrasting color bands arranged spirally on their curved surfaces; pinions rotatable on said studs and fixed to said color member; a gear engaging said pinions; means for rotating said wheel; and means for rotating said gear at a slightly different speed from that of said wheel.

3. A chromatic blender including a rotatable wheel having radial studs thereon; conical members rotatable on said studs and having contrasting color bands on their curved surfaces; means for rotating said wheel at relatively high speed; and means for rotating said color members on said studs at relatively low speed.

4. A chromatic blender including a base; a shaft 20 rotatably mounted on said base; a wheel fixed on said shaft and having radial studs; conical color members rotatable on said studs and having contrasting color bands arranged spirally on their exposed areas; bevel pinions rotatable on 25 said studs and fixed to said color members; a bevel gear rotatably mounted on said shaft and enmeshed with all of said pinions; and means for rotating said shaft and said gear at slightly different speeds.

5. A chromatic blender including a rotatable wheel having studs projecting therefrom; conical members rotatable on said studs and having contrasting color bands on their curved surfaces; means for rotating said wheel at relatively high 35 speed; and means for rotating said color members on said studs at relatively low speed.

REGINALD GILBERT.
